WILLARD J. DUNSTON, OF SOMERVILLE, MASSACHUSETTS

VALVE LIFTER

Application filed October 5, 1928. Serial No. 310,632.

This invention relates to a device designed and adapted to be operated in conjunction with spring-actuated poppet valve members of an internal combustion engine or air compressor to compress their springs, for the purpose of removing and replacing the keys which hold the springs in place on the stems of the valve members, and also to enable the grinding of the valve members while in operative position, or to enable the removal of the valve members for grinding the same or for replacing them.

The principal object of the invention is the provision of a device of the indicated character of improved, simple and rugged construction, and among the advantages of the use of the device, are the following: Affords rigidity with a positive vertical lift with no side or lateral thrust or cocking or canting movement sufficient to bend or spring the stems of the valve members; extreme power, durability and simplicity in operation; capable of being put in one set position and yet reach all of the valve members with equal accessibility regardless of the manifold, carburetor or other projections or attachments of the engine, due to the rigidity of the device when set in position to insure the positive lock at any height of lift, and virtually eliminating the possibility of injury to the operator through slipping; and to assure the ready removal and replacement of the keys which hold the retracting springs in place without springing or bending the stems of the valve members while performing the compression operations.

The nature of the invention and its distinguishing features and advantages will appear when the following specification is read in connection with the accompanying drawings, in which

Figure 1 is a view illustrating the device in use;

Fig. 2 is an enlarged view of the device attached to a cylinder block and swung out from the block, and showing different positions of the lifting arm and its operating means;

Fig. 3 is an enlarged sectional view with a portion of the swinging arm being broken

away and the lifting arm being shown in the down position;

Fig. 4 is a plan view of the device.

Referring now more particularly to the several views of the drawings, it will be apparent, that the device includes an attachment 10 in the form of a block, base or bracket adapted to be rigidly or fixedly secured in position on the cylinder block of an engine, such cylinder block being designated 11. The attachment 10 consists of relatively angularly disposed members 12, 12, and 13. The member 13 is provided with an elongated slot 14 for the reception of one or more of the bolts which serve to hold the head of the cylinder block in place. Such bolt is designated 15 and is provided with the necessary sleeve and nut 16 and 17, respectively, for effectively clamping the attachment 10 in place on the block 11. The attachment 10 has secured thereto or formed integral therewith a spindle 18. An arm 19 is arranged for swinging or pivotal movement on the spindle 18 and is held from becoming separated from the spindle 18 by a washer 20 and stud bolt 21, the latter being screwed into a threaded bore in the spindle 18. A slide 22 is arranged for sliding movement on the arm 19 the full length thereof, and is provided with a depending vertically disposed spindle 23. A lifting arm 24 is provided with means 25 at one end adapted to receive the stem of a valve member and to engage and exert pressure on a retracting spring on the stem of such valve member. The opposite end of the arm 24 is provided with a sleeve 26 which fits the spindle 23, and is slidable up and down thereon and so mounts the arm 24 for up-and-down movement. The upper end of the sleeve 26 is provided with a shoulder 27, and a collar 28 which rests on the shoulder 27, the collar 28 being held in place by a nut 29 screwed on the threaded extremity of the sleeve 26. It will be apparent that the arm 24 is not only mounted for up-and-down movement, but that it may swing or pivot on the spindle 23, the upper end of the sleeve 26 turning in the collar 28.

In order to effect the up-and-down movement of the arm 24, and to releasably hold

the arm in different lifting positions against downward movement there is provided means presently to be described. Secured to or formed integral with the slide 22, is a toothed segment of rack 30. A lever 31 is associated with the toothed segment 30. The lever 31 includes a fulcrum or pivot 32 carried by the segment 30 and said lever 31 is also provided with a hollow handle 33. The lever 31 is connected with the collar 28 by links 34, each of which is pivotally connected at one end as at 35 with the collar 28, and pivotally connected at the opposite end with the lever 31 as at 36. A pawl 37 is connected with the lever 31 for pivotal movement as at 38, and said pawl is adapted to coact with the teeth of the segment 30. A rod 39 extends through the handle 33 of the lever, and the lower end thereof is pivotally connected as at 40 with the pawl 37, and the upper end of the rod is provided with a button 41. The button 41 may be manipulated to disengage the pawl 37 from the teeth of the segment 30, and a spring 42 which surrounds the rod 39 and which has one end in engagement with the handle 33 and the opposite end in engagement with the button 41 serves to retract the rod 39 and incidentally move the pawl 37 in engagement with one of the teeth of the segment 30.

From the foregoing it will be apparent that the device may be readily attached in set position on the cylinder block 11 to the end that the device will be rigid yet enabling an operator to apply a positive vertical lift for the purpose of compressing a retracting spring indicated at 43 surrounding the stem 44 of a poppet valve member without liability of bending or springing the same; that the key 45 of the stem which holds the spring 43 in operative position associated with the stem 44 may be readily removed to be replaced by another whenever the occasion arises, or to enable the operator to readily remove the valve member for any purpose; that the lifting arm 24 may be releasably held at any desired lifting position through and by virtue of the manipulation of the lever 31 and by manipulating the button 41 in one and the same operation; and that the lifting arm 24, due to the provision of the swinging arm 19 and sliding spindle 23, may be brought within reach of any of the valve members with equal accessibility and permitting the same facility of operation for the intended purpose.

What is claimed is:

1. In a device of the class described, an attachment adapted to be fixedly secured to the cylinder block of an engine, an arm pivotally mounted on said attachment, a lifting arm provided with means on one end for the purpose of compressing a spring on the stem of a valve member of the engine, coacting means on the first mentioned arm and the lifting arm mounting the lifting arm for

sliding movement, swinging movement and guided up and down movement with respect to the first mentioned arm, and means operable to effect the up and down movement of said lifting arm.

2. In a device of the class described, an attachment adapted to fixedly secured to the cylinder block of an engine, an arm pivotally mounted on said attachment, a lifting arm provided with means on one end for the purpose of compressing a spring on the stem of a valve member of the engine, coacting means on the first mentioned arm and the lifting arm mounting the lifting arm for sliding movement, swinging movement and guided up and down movement with respect to the first-mentioned arm, means operable to effect the up and down movement of said lifting arm, and means operable to hold the last mentioned means from moving for the purpose of holding the lifting arm in different lifting positions.

3. In a device of the class described, an attachment provided with means for fixedly securing it in a set position, a lifting arm, means connecting said lifting arm with said attachment for swinging and guided up and down movements with respect to said attachment, means operable to effect the up and down movement of the lifting arm, and means operable to hold said lifting arm in and to release it from different lifting positions.

4. In a device of the class described, means including a spindle adapted to be fixedly secured in a set position, an arm mounted on said spindle for pivotal movement, a slide arranged on said arm for sliding movement, said slide having a depending spindle, a lifting arm arranged for swinging and guided up and down movements on said depending spindle, means carried by said slide and connected with said lifting arm operable to effect the up and down movement of said lifting arm, and also to releasably hold said lifting arm in different lifting positions.

5. In a device of the class described, means including a spindle adapted to be fixedly secured in a set position, an arm mounted on said spindle for pivotal movement, a slide arranged on said arm for sliding movement, said slide having a depending spindle, a lifting arm having a sleeve arranged on said depending spindle to mount said lifting arm for swinging and guided up and down movements on said depending spindle, a lever carried by said slide, a loose collar carried by said sleeve, links each having the opposite ends thereof pivotally connected respectively with said lever and collar to effect the up and down movement of the lifting arm in response to the operation of said lever, and coacting means on the lever and slide operable to releasably hold the lifting arm in different lifting positions.

6. A device of the class described, compris-

ing an attachment adapted to be fixedly secured, a supporting arm mounted on said attachment, a work performing arm, a slide on said supporting arm, coacting means on said slide and work performing arm mounting said work performing arm for pivotal movement and up and down movement, and means operable to effect the up and down movement of said work performing arm.

10 7. A device of the class described, comprising an attachment adapted to be fixedly secured, a supporting arm mounted on said attachment, a work performing arm, a slide on said supporting arm, coacting means on said slide and work performing arm mounting said work performing arm for pivotal movement and up and down movement, means operable to effect the up and down movement of said work performing arm, and means
15 adapted to cooperate with the last mentioned means to releasably hold the work performing arm in different positions.
